UNITED STATES PATENT OFFICE.

CARL A. OLSON, OF CLARINDA, IOWA, ASSIGNOR TO CLARINDA MANUFACTURING COMPANY, OF CLARINDA, IOWA, A CORPORATION OF IOWA.

MOTOR SUPPORT FOR WASHING MACHINES.

Application filed October 15, 1923. Serial No. 668,694.

To all whom it may concern:

Be it known that I, CARL A. OLSON, a citizen of the United States of America, and resident of Clarinda, Page County, Iowa, have invented a new and useful Motor Support for Washing Machines, of which the following is a specification.

The object of this invention is to provide new and improved means for mounting and supporting an electric motor on and relative to a washing machine and relative to speed-reducing gearing employed in the operation thereof.

A further object of this invention is to provide an improved motor support including means for directly connecting a motor casing to a gear housing and auxiliary means carried by a machine element for relieving strain on the main support.

My invention consists in the construction, arrangement and combination of elements hereinafter set forth, pointed out in my claims and illustrated by the accompanying drawing, in which—

Figure 1 is an elevation showing a portion of a washing machine and driving mechanism therefor, together with an electric motor and my improved support therefor in position for practical use, some of the elements being shown in section. Figure 2 is an elevation, partly in section, at right angles to Figure 1.

In the construction and mounting of the device as shown the numeral 10 designates the tub of a washing machine having a cover member 11 on which is mounted a casting 12 forming a portion of the support for the driving mechanism and also a gear housing 13. In this instance a train 14 of spur gearing is shown in the housing 13, through which power is transmitted to the driving mechanism at reduced speed from an electric motor 15, on the shaft 16 of which is a bakelite pinion 17 located within the housing 13 and meshing with the first member of the train 14. The motor is located at one side of and near the top of the tub 10 and the shaft 16 thereof is arranged in a horizontal plane and extends toward a portion of the gear housing 13 which projects laterally from the tub.

A substantially L-shaped cradle is provided for the motor and includes a horizontal arm 18 extending beneath and substantially in the plane of the axis of the

motor, and a vertical arm 19 integral with and extending upwardly from said horizontal arm and crossing the axis of the motor shaft. Wings 20, 21 preferably are formed on and extend oppositely from the horizontal arm 18 of the cradle, said wings engaging the lower surface of the motor, in certain instances being curved to conform to the curvature of the motor, as here shown, or they may be otherwise shaped to fit the motor case, to which they may be attached by means of screws 22. The vertical arm 19 of the motor cradle is formed at its upper end with a circular head 23 formed with a central circular hole 24 of sufficient diameter to permit the free passage of the motor shaft 16. The head 23 is formed on its face adjacent the motor with a counterbore 25 or recess concentric with its bore 24, adapted to receive snugly a circular boss 26 formed on the end of the motor case concentric with the shaft 16. On its opposite face the head 23 is formed with a circular boss or projection 27 adapted to fit snugly with a circular hole 28 in the adjacent wall of the gear housing 13. The head 23 is formed with diametrically opposed tapped holes 29, 30 adapted to be brought into alignment with registering holes formed in the opposed walls of the gear housing 13, which is flat and relatively narrow as shown in Figure 1. Cap screws 31, 32 are adapted to be mounted through the holes in the walls of the housing 13 and seated in the tapped holes 29, 30 of the head 23 of the motor cradle, said cap screws being spaced sufficiently to clear the pinion 17.

The pinion 17 is mounted on the shaft 16 after the motor is mounted on its cradle, and then the assembly is attached to the machine by inserting the boss 27 of the head 23 in the opening 28 of the housing and inserting the cap screws 31, 32. This connecting means is sufficient to support the normal weight of the motor and also insures proper alinement and centering of the shaft and pinion relative to the gears in the housing.

It is desirable, however, to provide an auxiliary support for the motor to guard against undue strains such as the placing of additional weight thereon and against impact of foreign objects. An L-shaped bracket 33 is mounted against the side of the tub 10 and held in place by bolts, screws or other securing means, 34. The horizontal

arm of the bracket 33 extends beneath and across the horizontal arm 18 of the motor cradle, and an adjusting screw 35 is threaded in said bracket arm, from below, and 5 adapted to engage at its end the lower surface of said arm 18, to furnish additional and adjustable supporting means for the cradle and motor, at a point spaced materially from the suspending connection to the 10 gear housing. The adjusting screw 35 may be provided with a lock nut 36. A wedge-shaped member 37 is mounted against the vertical arm of the bracket 33 and is formed with a longitudinal slot 38 through which 15 passes a bolt 39 engaging said arm, whereby the member is adjustably supported on the bracket. The wedge-shaped member 37 has an inclined outer face adapted to engage beneath the curved side of the motor case 20 and assist in supporting the same.

I claim as my invention—

1. The combination with a motor and a driving mechanism having a housing, of a supporting means for said motor comprising a cradle having one arm extending beneath said motor and the other arm formed with a flat head projecting between the motor and housing and provided with an opening for the passage of the motor shaft, 25 said head being formed on one face with a boss received snugly in an aperture in said housing and on its opposite face with a counterbore receiving snugly a boss on said motor, and cap screws extending through 30 said housing and seated in said head.

2. The combination with a motor and a driving mechanism having a housing, of a supporting means for said motor comprising a cradle having one arm extending beneath said motor and the other arm formed with a flat head projecting between the motor and housing and provided with an opening for the passage of the motor shaft, 40 said head being formed on opposite faces 45 with slip-joint connections between said motor and housing respectively, securing means between said housing and head, and

an auxiliary support comprising a bracket extending beneath said motor arm having an adjusting screw adapted for engagement 50 therewith.

3. The combination with a motor and a driving mechanism having a housing, of a supporting means for said motor comprising a cradle having one arm extending beneath said motor and the other arm formed with a flat head projecting between the motor and housing and provided with an opening for the passage of the motor shaft, 55 said head being formed on opposite faces with slip-joint connections between said motor and housing respectively, securing means between said housing and head, and an auxiliary support including a fixed bracket and a wedge shaped member 60 adjustably mounted on said bracket and adapted for engagement with said motor.

4. The combination with a motor and a driving mechanism having a housing, of a supporting means for said motor comprising a cradle having one arm extending beneath said motor and another arm projecting between the motor and housing and formed with slip-joint connections with each, 70 securing means between said housing and last 75 named arm, and an auxiliary support including a bracket having an arm projecting beneath said motor, an adjusting screw threaded in said arm and adapted for supporting engagement with the motor, and a wedge 80 adjustably mounted on said bracket and adapted for engagement with a curved side of the motor.

5. A motor support, comprising a bracket having an arm adapted to extend beneath 85 a motor, a screw threaded in said arm and adapted for adjustment to engage said motor, and a wedge member adjustably mounted on a vertical arm of said bracket 90 and adapted to engage a curved side of the motor.

Signed by me at Clarinda, Page County, Iowa, this 31st day of July, 1923.

CARL A. OLSON.
